UNITED STATES PATENT OFFICE

WILLIAM A. HAVEN, OF YOUNGSTOWN, OHIO

HEAT EXCHANGING DEVICE

Application filed December 4, 1929. Serial No. 411,461.

This invention relates to heat exchanging apparatus, and more particularly insert bodies or plates capable of being placed in a wall to assist in the temperature control thereof; and it is among the objects of the invention to provide a construction affording a plurality of independent fluid passages. Another object is the provision of a device affording efficient heat transfer and being at the same time capable of sustaining considerable loads. Other objects and advantages will appear as the description proceeds.

To the accomplishment of the foregoing and related ends, the invention, then, consists of the features hereinafter fully described, and particularly pointed out in the claims, the following description and the annexed drawings setting forth in detail certain structures embodying the invention, such being illustrative however of but a few of the various ways in which the principle of the invention may be employed.

In said annexed drawings:—

Fig. 1 is a fragmentary sectional view of a furnace wall showing my improved device in place therein; Fig. 2 is a rear elevation of one form of the device; Fig. 3 is a horizontal section taken on a plane indicated by the line III—III, Fig. 2; Fig. 4 is an axial section taken on a plane indicated by the line IV—IV, Fig. 3; Fig. 5 is a rear elevation of another form; Fig. 6 is a horizontal section thereof taken on a plane indicated by the line VI—VI, Fig. 5; and Fig. 7 is a longitudinal section taken on a plane indicated by the line VII—VII, Fig. 6.

Referring more particularly to the drawings, there is shown in Fig. 1 a portion of a furnace wall 2 of masonry, firebrick, etc., the further detail being immaterial to the present invention. In the wall are temperature control plates 3, having pipe connections 5, etc. for inlet and outlet of fluid, header pipes (not shown) continuing on from these as desired to the source of supply and the final discharge respectively. The plates 3 or essentially chambered hollow bodies are provided with passageways, and have lower walls 6, upper walls 7, the latter being preferably arched where the load to be carried is con-

siderable, and side walls 8. Rear wall 9 and front wall or nose 10 complete the boundaries. The chamber system within involves a plurality of independent passageways, one being arranged to lie adjacent the forward or inner end 10 and another lying rearwardly thereof. In the form shown in Figs. 2, 3 and 4, the forward passageway is set off by a partition 11, and to the rear thereof further staggered partitions 12, 13, provide an extended passageway system B, entirely independent of the passageway system A. The passage A as thus laid out has lateral portions a, adjacent the side walls, this entire system then forming a loop from the rear around adjacent the side wall to the forward end, and thence back adjacent the other side wall to the rear. Openings 14 and 15, preferably tapped for pipe connections, provide an inlet and an outlet for such passage. The passageway B has likewise openings 16, 17 for pipe connections, and by arranging the inlet at 16, the lead b of the passageway conducts the fluid forwardly to return thence about the baffle partitions 12, 13 to outlet 17.

An additional opening 18, preferably placed at the highest point of the arch is desirable, being available for an additional discharge or feed line; or where heavy duty circulation is not required, such opening is available as a cleanout and may be normally closed with a plug.

With the respective passageways through the body of the plate entirely independent of each other, each having its own valve-controlled feed and discharge, it will be seen that not only may a stepwise or graduated temperature control be maintained if desired, but more particularly, in the event of a break in passage A or passage B, the former being most vulnerable, the remaining passage is still capable of functioning, and a complete loss of control at this point is avoided. For instance, in the event of a burnout or rupture at the wall 10, disabling the passage A and necessitating the shut-off of fluid thereto, the passage system B is still effective, and by the additional opening 18 its rate of circulation may be in fact accelerated in compensation so far as possible, and operation can be con-

- tinued until a convenient opportunity for renewal is had. Apertured lugs 19 are of convenience in such handling of the unit as may be at any time necessary.
15. In the form shown in Figs. 5, 6 and 7, the forward passageway A' has its discharge and supply through leads a', openings 14', 15', preferably tapped for pipe connections providing inlet and outlet. The passageway B' is again formed by baffle partitions 12', 13' extending in a generally transverse direction, and openings 16', 17' provide inlet and outlet to pipe connections. Auxiliary opening 18', again, preferably at the highest point of the arch, allows of usage as a cleanout, or for additional circulation as required. In this construction, the conduits a' have the further advantage of a positioning where especially well protected by the cooling water of the rear compartment.
20. It will thus be seen that plate constructions may be had in which independent passageways allow of fluid circulation, such that in the event of failure of one, functioning may be carried on with the remainder, and the construction is such furthermore as to make possible the carrying of heavy loads such as may be encountered in masonry walls of furnaces, with bosh plates and the like.
25. Other modes of applying the principle of the invention may be employed, change being made as regards the details disclosed, provided the means stated by any of the claims, or the equivalent of such, be employed.
30. I therefore particularly point out and distinctly claim as my invention:—
1. A bosh plate, comprising a shallow metallic body having upper and lower masonry-engaging walls and containing partitioning forming a fluid chamber at the forward end of the body, and another independent chamber rearwardly of the first-named chamber having transverse staggered baffles arranged to produce a sinuous circulation of the cooling fluid, and an inlet and outlet for each chamber independently.
2. A bosh plate, comprising a shallow metallic body having upper and lower masonry-engaging walls and containing partitioning forming a fluid chamber extending around the sides and forward end of the body and another independent chamber rearwardly of the first-named chamber and having staggered transverse baffles arranged to produce a sinuous circulation of the cooling fluid, and an inlet and outlet for each chamber independently.
3. A bosh plate, comprising a shallow metallic body having upper and lower masonry-engaging walls, and containing transverse partitions, one forming a fluid chamber at the forward end of the body and another independent chamber rearwardly of said first-named chamber, the rest of said transverse partitions being disposed as trans-
- verse baffles arranged to produce a sinuous circulation of the cooling fluid in said rear chamber, integrally-formed ducts passing through said partitions and forming an inlet and outlet supply for the forward chamber, and an independent inlet and outlet for the rear chamber.
- Signed by me this 2nd day of December, 1929.
